UNITED STATES PATENT OFFICE.

JAMES J. READING, OF DETROIT, MICHIGAN, ASSIGNOR TO CENTRAL CONTRACTING & ENGINEERING CO., OF DETROIT, MICHIGAN, A CORPORATION OF MICHIGAN.

SECTIONAL TRACK FOR ROAD VEHICLES.

Application filed January 16, 1928. Serial No. 247,185.

My invention relates to a sectional track for road vehicles, which track is adapted to be laid over comparatively rough ground without substantial grading and which is sufficiently flexible to roughly accommodate itself to inequalities in the surface of the ground and which is adapted to support and carry a road vehicle and to guide the travel thereof over the track.

10 One object of such a track is to provide means for driving a road vehicle alongside of construction work which is constantly being extended over new ground as, for example, the construction of sewers or the like. In 15 this respect it takes the place of the dolly track and equipment which is commonly used to bring construction materials to a job.

My improved track will support any type of road vehicle and permits the material to 20 be brought directly from the train to the job upon which it is to be placed and the track may be extended as necessary to meet the requirements of the work. It is readily laid and quickly removed.

25 The above advantages and meritorious features will be more fully explained as will other additional advantages in the following specification, appended claims and accompanying drawing, wherein

30 Fig. 1 is a perspective of a rail.

Fig. 2 is a perspective of a tie.

Fig. 3 is a plan of a fragment of the track.

Fig. 4 is a transverse sectional view through the fragment of track shown in Fig. 3.

35 Fig. 5 is a longitudinal sectional view through a fragment of the track shown in Fig. 3.

Fig. 6 is a side elevation of a portion of the track.

40 I provide a series of ties 10, each of which carries at opposite ends a pair of abutments 12. These abutments are here shown as being formed of angle iron sections secured by bolts or screws 14 to the ties. The abutments 45 of each pair are so spaced apart as to receive therebetween one of the rails and the two pairs of abutments are so spaced apart as to position the two rails of the pair. One of the rails is indicated in Fig. 1 and it comprises a base or bottom 18 and an upright portion or flange 20. The bottom of the rail is provided with depending abutments 22 which are here shown as formed of angle iron sections secured or otherwise fastened to the rail.

The rails are relatively short and I have 55 here shown each rail as supported by four ties. Two of these ties extend underneath an intermediate portion of the rail and the abutments 22 are here shown as arranged in pairs below such intermediate section of the rail 60 to engage opposite sides of each tie to space the ties apart.

The opposite ends of the rails terminate substantially midway over a tie which is common to a continuing pair of rails. Each rail 65 has one of its abutments 22 positioned in proximity to its end and so spaced therefrom as to engage one side of this common tie as indicated in the figures of the drawing. The continuing pair of rails is similarly supported 70 upon ties and the rails of this pair are provided with end abutments similarly arranged to assist in positioning that tie which is common to both pairs of rails.

75 The ties and rails are so interlocked by their respective abutments as to prevent spread of the rails upon the ties and to position the end ties which are common to succeeding rails. There may also be provided, as shown, additional abutments to engage the 80 ties completely crossed by the rails, if this is desired. The rails are so supported upon the ties as to be readily removable to facilitate laying of the track and the breaking up of the track. The rails being short and the construction being as indicated, it is apparent 85 that the track will conform more or less roughly to the contour of the ground and will not require careful grading of the ground. It possesses flexibility due to the permitted 90 vertical play which accomplishes this end.

What I claim is:

1. A sectional road vehicle track comprising a plurality of ties each provided with spaced apart pairs of abutments, one pair in 95 proximity to each end, a pair of L-shaped rails removably supported upon said ties between the abutments thereof with the ends of the rails positioned substantially midway over a tie, each rail provided with depending 100 intermediately disposed abutments engaging opposite sides of the ties crossed by the rails and end abutments engaging that side of the tie at the end of the rails crossed by the rails, and successive pairs of rails similarly supported upon ties as continuations of the first 105 pair of rails and supported in part upon the same end ties.

2. A sectional road vehicle track comprising a plurality of ties, a pair of rails removably supported thereupon and freely detachably connected therewith to prevent spread of the rails upon the ties or spread of those ties completely crossed by the rail, a second pair of rails similarly supported upon ties as a continuation of the first pair of rails and a tie positioned underneath the meeting ends 10 of the two pairs of rails and held in place by abutments formed on said rails.

3. A road vehicle track comprising a plurality of ties, a pair of L-shaped rails removably supported thereupon with their upright 15 flanges arranged to guide the travel of the vehicle thereover, said ties having upright abutments engaging the rails to prevent the spread thereof and said rails having depending abutments engaging certain of the ties to 20 prevent the spread thereof.

4. A road vehicle track comprising a plurality of ties, a pair of L-shaped rails removably supported thereupon with their upright flanges disposed on the outside to guide the 25 travel of a vehicle therebetween, said rails and ties detachably interlocked to prevent the

spread of the rails upon the ties or the spread of the end ties underneath the rails.

5. A sectional road vehicle track comprising a plurality of ties, a pair of rails having upright flanges and being removably supported upon the ties and loosely interlocked therewith to prevent the spread of the rails while permitting vertical play thereof, a second pair of rails similarly supported upon and interlocked with a second series of ties as continuations of the first pair of rails, said two pairs of rails having their meeting ends supported upon a common tie and loosely interlocked therewith to prevent displacement 40 thereof.

6. A sectional road vehicle track comprising a plurality of ties, a plurality of relatively short pairs of rails arranged end to end upon the ties and loosely interlocked therewith to prevent spread of the rails while permitting relative vertical play whereby the track may accommodate itself roughly to the contour of the ground over which it is laid.

In testimony whereof, I, JAMES J. READING, 50 sign this specification.

JAMES J. READING.
